UNITED STATES PATENT OFFICE.

JOHN J. DUFFIE, OF SAN FRANCISCO, CALIFORNIA.

VACUUM-CLEANER.

1,021,667.

Specification of Letters Patent. Patented Mar. 26, 1912.

Application filed November 6, 1909. Serial No. 526,548.

To all whom it may concern:

Be it known that I, JOHN J. DUFFIE, a citizen of the United States, residing at 369 Market street, San Francisco, in the 5 county of San Francisco and State of California, have invented a new and useful Vacuum-Cleaner, of which the following is a specification in such full and clear terms as will enable those skilled in the art to construct and use the same.

This invention relates to a vacuum cleaner and the object is to produce a machine which will at once be light, compact, portable and which will have a capacity to 15 produce a comparatively high vacuum the fans being arranged with that special object in view.

Another object of the invention is to produce a machine which will be cheap in construction, and which may be easily cleaned or examined when so desired.

Another object of the invention is to produce a machine which may be used for the purpose of blowing the dust out of corners, 25 or for other like purposes when desired, a special attachment making possible the utilization of the air current either as a blast or as suction at the will of the person using the same.

30 In the drawings in which the same numeral of reference is applied to the same portion throughout the several views, Figure 1 is a vertical sectional view through the casing of the machine showing its interior construction, Fig. 2 is a view of a hose attachment used for the purpose of attaching to the casing of the machine when the air blast is to be used, Fig. 3 is a view of one of the fans used, and Fig. 4 is a detail view showing the manner of securing the dust collecting bag in the top of the casing.

The numeral 1 represents the casing of the machine which may be of any desired 45 shape, as square or cylindrical, said casing having rubber feet 2 at the bottom thereof to prevent it from marring polished floors. In the bottom of the casing there is a motor M which is centrally placed with respect 50 to said bottom, there being partitions 3 on each side of the motor to confine the air in the desired manner. Each partition has a hole 4 therein adjacent the ends of the motor shaft, and a short inclined floor 5 55 is connected with one of said partitions for

the purpose of preventing any dirt from accumulating in the base of the machine.

The motor is provided with a horizontal shaft 6 on each end of which is a fan 8. It will be noted that the blades of each fan 60 are adjacent their respective partitions, while the disks 7 thereof are the width of the fan blade away therefrom, the object being to provide means whereby the vacuum produced may be increased, since one fan 65 takes the air from the dust collecting bag and delivers it to the intake of the second fan, thus increasing the amount of air moved since one fan works against a lower pressure than it otherwise would. In order that the air may be confined at the top of the motor in the proper manner a horizontal partition 9 fits tightly in the casing, said partition having small angle plates 10 secured thereto and having packing 11 between said plates whereby an air tight fit 70 is secured. In order that the partition 9 may be removed from the machine for inspection thereof it is provided with a handle 12.

The upper portion of the machine is for the collection of the dust and dirt which is taken from the floor by the machine when the same is used. In the upper part of the casing there is placed a wire basket 13 which 85 rests on the top of the handle 12 and on brackets 14 at the sides of the casing near the top thereof. This basket is for the purpose of holding the dust collecting sack 15 away from the sides of the casing so that 90 it will at all times be free to discharge the air while preventing the discharge of dust therethrough. The sack has its upper edges secured to a hoop 16, which fits tightly in the casing and prevents the air from passing to the fans except through the body of 95 the sack.

The cover 17 of the machine fits tightly in the top of the casing and is held therein simply by friction thereon and it is provided at the center thereof with an inlet pipe 18, covered with a glass dome 19, said dome being for the purpose of examining the incoming dust laden air to see when the cleaning operation has been completed. 100 A hose 20 is secured in the open end of the inlet pipe and suitable tools are used for the collection of dust and dirt from all places, as carpets, drapery, etc. In order 105 that the machine may be easily carried from 110

place to place it is provided with a bail 21 having a handle 22 thereon.

Since it frequently happens that persons wish to use the machine as a blowing machine instead of as a suction cleaning machine a fitting 23 is provided which screws into a bushing 24 in the side of the machine 5 in front of the secondary fan, a hose 25 being attached to the said nozzle and being of 10 any desired length.

Having thus described my invention what I claim as new and desire to secure by Letters Patent of the United States is as follows:

- 15 1. In a vacuum cleaner, a casing, a motor in said casing, a shaft operated by said motor, a fan on each end of said motor shaft, a partition adjacent each fan, a removable diaphragm in said casing, and 20 adapted to form airtight joints with said partitions, a cover for said casing, and an air and dust inlet pipe in said cover, substantially as described.
2. In a vacuum cleaner, a casing, a motor 25 in said casing, a shaft operated by said motor, a fan on each end of the motor

shaft, a partition adjacent each fan, a diaphragm in said casing adapted to form airtight joints with the said partitions, a cover for said casing, and an air and dust inlet pipe in said cover, substantially as set forth.

3. In a vacuum cleaner, a casing, a motor therein, a shaft operated by the motor, a plurality of fans on said motor shaft, one of said fans having its intake connected 35 with the upper portion of the casing and discharging into the intake of another of said fans, a removable partition above said motor and fans separating them from the intake chamber, a removable cover for the 40 casing forming a compartment in the upper portion thereof, and an air and dust inlet pipe into said compartment, substantially as described.

In testimony whereof I have hereunto set 45 my hand this 25th day of October, A. D. 1909, in the presence of the two subscribed witnesses.

JOHN J. DUFFIE.
